TELEVISION PROCESS

Manfred von Ardenne, Berlin, Germany, assignor
to Radioaktiengesellschaft D. S. Loewe, Berlin-
Steglitz, Germany, a company of Germany

Application December 23, 1931, Serial No. 582,737
In Germany December 22, 1930

1 Claim. (Cl. 178—7.7)

To obtain good and sharp images rich in contrast, it is, as well known, necessary to transmit an extremely large number of image points. The number of images capable of transmission is, in the practical execution, limited by difficulties of a technical kind, for example in the case of wireless television transmission by the frequency of the carrier wave, in cable transmission by the frequency dependency of the cable, by the leakage, etc. For television receivers the fact is also particularly disturbing that the image appears to be divided into strips, the faultless assembly of which may only be obtained with considerable difficulty.

15 This impression of the image divided into strips arises, as known, from the fact that the scanning ray sweeps over the picture, line after line and the inevitable intervals between those lines are left. An avoidance of the formation of such intervals, by partly covering or overlapping one line and the next line of the picture elements, has already been proposed for certain purposes, but has the disadvantage that the pictures seem to be faded and unclear.

20 The subject matter of the present invention is a method, by means of which these difficulties are overcome.

For this purpose the image, upon the transmission, is divided into strips, which are not situated 25 permanently at the one point, but pass continuously over the image. For example, in the case of television processes employing Braun tubes the scanning cathode ray, which passes, for example, sinusously over the surface, or irradiates the 30 surface in relaxation oscillations (which have a straight-line wave form), is deflected, transversely or perpendicularly to its direction, by a frame frequency in respect of which the line frequency amounts to a non-integral multiple.

35 In the described type, for instance, in one frame the scanning control begins at the beginning of the first line, whereas in the following frame it does not begin at the beginning of the line, but at another place within the line. The 40 displacement increases from frame to frame according to the ratio of line frequency to frame frequency. The wandering of the scanning strips from one frame to the next effects the appearance 45 of a completely equal or uniform scanning. At the same time the transmitted image reveals extremely fine marking.

50 This method is of particular advantage when

employing amplifiers, which are incapable of transmitting low frequencies.

In the drawing Fig. 1 illustrates an arrangement in which the present invention can be adapted, and Fig. 2 shows, in diagrammatic fashion, the scanning of two successive frames. In Fig. 1, 1 represents a Braun tube, containing the cathode 2, the Wehnelt-cylinder 3, the anode 4, the deflecting plate-pairs 5 and 6 as well as the fluorescent screen 7. The cathode 2 is heated by means of a battery 8. 9 designates an anode battery and 10 an initial potential battery for the Wehnelt-cylinder 3, which is supplied over a transformer 11 with the voltages controlling the cathode ray-intensity. The relaxation (straight line 15 wave form) oscillations produced by the generators 12 and 13 are conducted to the deflecting plate pairs 5 and 6. The frequency of the line-frequency oscillation generator 12 amounts according to the invention to a non-integral multiple 20 of the frequency of the image frequency or frame frequency oscillation generator 13.

Fig. 2 shows diagrammatically the scanning of two successive frames, and in this view the scanning strips are indicated by hatching while the intervening gaps are unhatched. By comparing the diagram of one frame (marked 1) with that of the other or second frame (marked 2), the shifting or displacement of the scanning strips from one frame to the next will be observed readily, particularly when comparing the position of the said strips at the upper and the lower edges of the two frame diagrams.

30 I claim:

The method of scanning a succession of related 35 television picture frames in a definite frame frequency with the aid of an oscillating cathode ray, which comprises causing such ray to scan first one of such frames along a series of lines exhibiting a definite line-frequency arrangement, such line 40 frequency being a non-integral multiple of the frame frequency, then to scan the next frame along a series of lines exhibiting a line frequency arrangement similar to that of the scanning lines of the preceding frame but, owing to said relation of line frequency to frame frequency, shifted 45 so that the scanning of such next frame will begin at a point of the line different from that at which the scanning of the preceding frame began, and repeating this operation progressively from frame 50 to frame.

MANFRED VON ARDENNE.
